[57] CLAIM

The ornamental design for an information display sign
mounted on vehicles, as shown and described.

DESCRIPTION

FIG. 1 is a perspective view of the information display
sign mounted on vehicles showing our new design;

FIG. 2 is a front elevational view thereof;

FIG. 3 is a rear elevational view thereof;

FIG. 4 is a side elevational view thereof, the side oppo-
site being a mirror image of the side shown in FIG. 4;

FIG. 5 is a top plan view thereof; and,

FIG. 6 is a bottom plan view thereof.

FIG. 1

FIG. 3

FIG. 2

FIG. 5

FIG. 6

FIG. 4
